UNITED STATES PATENT OFFICE

THOMAS O. SCHRADER, OF ALLENtown, PENNSYLVANIA, ASSIGNOR TO THE DENT HARDWARE COMPANY, OF FULLERTON, PENNSYLVANIA, A CORPORATION OF PENNSYLVANIA

DESIGN FOR A LATCH AND KEEPER COMBINATION

Application filed November 9, 1932. Serial No. 45,855. Term of patent 3½ years.

To all whom it may concern:

Be it known that I, THOMAS O. SCHRADER, a citizen of the United States, residing at Allentown, in the county of Lehigh and State of Pennsylvania, have invented a new, original, and ornamental Design for a Latch and Keeper Combination, of which the following is a specification, reference being had to the accompanying drawing, forming a part thereof.

cluding my new design of latch and keeper.

Figures 2 and 3 are elevation views looking from the top and bottom respectively at the combination illustrated in Figure 1.

Figures 4 and 5 are elevation views looking from the left and right side of the combination of Figure 1.

I claim:

The ornamental design for a latch and keeper combination as shown.

THOMAS O. SCHRADER.
